UNITED STATES PATENT OFFICE.

EMMA M. REQUA, OF HARRISON, NEW YORK.

DESIGN FOR A BADGE.

SPECIFICATION forming part of Design No. 21,618, dated June 7, 1892.

Application filed April 8, 1892. Serial No. 428,392. Term of patent 3½ years.

To all whom it may concern.

Be it known that I, EMMA M. REQUA, a citizen of the United States, residing at Harrison, in the county of Westchester, State of New York, have invented and produced a new and original Design for a Badge, of which the following is a specification, reference being had to the accompanying drawing, forming a part hereof.

10 The design is intended as a memento of the approaching World's Columbian Exposition to be held at Chicago in 1893.

The design, as shown in the accompanying drawing, consists of a representation in relief 15 of the head of Christopher Columbus, from which is suspended an annulus having a space, upon which may be placed any suitable inscription and within which is hung a representation of the Western Hemisphere. The 20 representation of the head is not in the ordi-

nary form of medal, but its shape is that of the contour of the head, neck, and collar, and presents a nearly full-faced view of the great explorer. The head is bare and the hair somewhat long, falling in locks over the ears. From 25 this representation of the head the annulus is shown suspended by ribbons and within the annulus a disk is suspended containing a representation of the Western Hemisphere.

Having thus fully described my new and 30 original design, what I claim is—

The design for a badge, substantially as herein shown and described.

In testimony whereof I have hereunto subscribed my name.

EMMA M. REQUA.
